(57) CLAIM

The ornamental design for an illuminated panel of a storage device housing, as shown and described.

DESCRIPTION

FIG. 1 is a perspective view of an illuminated panel of a storage device housing showing our new design; and,

FIG. 2 is a top plan view thereof.

The broken line showing of the remainder of the storage device housing is for illustrative purposes only and forms no part of the claimed design.

1 Claim, 1 Drawing Sheet
